UNITED STATES PATENT OFFICE.

ROSS L. TULLIS, OF NEW HAVEN, CONNECTICUT.

DESIGN FOR A BIRD CAGE.

Application filed February 3, 1925. Serial No. 12,253. Term of patent 14 years.

To all whom it may concern:

Be it known that I, Ross L. TULLIS, a citizen of the United States, residing in New Haven, New Haven county, Connecticut, have invented a new, original, and ornamental Design for Bird Cages, of which the following is a specification when taken in connection with the accompanying draw-

ings, of which the figure is a front elevational view of a bird cage embodying my new design.

I claim:

The ornamental design for a bird cage, substantially as shown.

ROSS L. TULLIS.
